UNITED STATES PATENT OFFICE.

TARGE G. MANDT, OF STOUGHTON, ASSIGNOR TO JOHN A. JOHNSON, OF MADISON, WISCONSIN.

WHIFFLETREE-HOOK.

SPECIFICATION forming part of Letters Patent No. 553,863, dated February 4, 1896.

Application filed March 9, 1895. Serial No. 541,168. (No model.)

To all whom it may concern:

Be it known that I, TARGE G. MANDT, a citizen of the United States, and a resident of Stoughton, in the county of Dane and State 5 of Wisconsin, have invented certain new and useful Improvements in Ferrules and Hooks for Whiffletrees; and I do hereby declare that the following is a full, clear, and exact description of the invention, which will enable 10 others skilled in the art to which it appertains to make and use the same, reference being had to the accompanying drawings, which form a part of this specification.

My invention relates to ferrules and hooks 15 for whiffletrees, and its object is to provide an improved construction of the ferrule with which the hook is connected, whereby it may be firmly secured to the whiffletree and prevented from turning thereon.

20 The ordinary method of attaching ferrules to whiffletrees is either to simply drive the same thereupon, relying upon frictional contact to hold them in place, or by passing a rivet diametrically through the ferrule and 25 the wood of the whiffletree. Both of these methods are objectionable, the first because the ferrule is not securely held in place, and the second because the rivet is liable to split the wood and weaken the whiffletree.

30 My invention is designed to obviate the above and other objections; and it consists in the novel construction and combination of parts, hereinafter fully described and claimed.

In the accompanying drawings, Figure 1 is 35 a perspective view of a whiffletree ferrule and hook constructed in accordance with my invention, showing the same secured to the end of a whiffletree. Fig. 2 is a perspective view of the same, showing it detached from 40 the whiffletree.

In the said drawings the reference-numeral 1 designates a whiffletree of any ordinary or suitable construction, and 2 the ferrule consisting of an annular band 3, formed with a shank 4, and a crescent-shaped hook 5, as 45 seen in Fig. 1. In Fig. 2 an eye 6 is substituted for the hook 5. The inner end of the ferrule 3 is formed with a semicircular flange 7, provided at its ends with prongs 8, which are driven into the whiffletree when the ferrule is placed on the end thereof. By this construction the prongs bite into the wood of which the whiffletree is composed, thereby preventing the ferrule from rotating or turning thereon, and also securely holding it in 50 place.

The ferrule and hook can be economically manufactured; it can be easily and readily applied to the whiffletree and the prongs clinched into the wood, and when in place 55 there is no liability of its turning or working loose on the whiffletree.

Having thus described my invention, what I claim is—

The combination with a whiffletree, of the 65 ferrule comprising the annular band, the semicircular flange formed integral therewith at the inner end, the prongs formed by slitting the ends of said flange, separating them from the band and bending them inwardly in 70 a plane parallel with the axis of the whiffletree and driving them into the whiffletree, substantially as described.

In testimony that I claim the foregoing as my own I have hereunto affixed my signature 75 in presence of two witnesses.

TARGE G. MANDT.
